UNITED STATES PATENT OFFICE.

RALPH H. BEACH, OF NEW YORK, N. Y., ASSIGNOR TO FEDERAL STORAGE BATTERY CAR COMPANY, OF NEW YORK, N. Y., A CORPORATION OF NEW YORK.

RAILWAY-CAR.

1,081,942.

Specification of Letters Patent. Patented Dec. 23, 1913.

Application filed February 21, 1911. Serial No. 610,068.

To all whom it may concern:

Be it known that I, RALPH H. BEACH, a citizen of the United States, and a resident of the borough of Manhattan, city of New York, county of New York, and State of New York, have invented certain new and useful Improvements in Railway-Cars, of which the following is a specification.

My invention relates to railway cars, and particularly to that type of electric railway car which is designed to be operated by storage batteries. In order that a railway car may be successfully operated by storage batteries, it is essential that the weight of the car itself be reduced to a minimum consistent with strength and rigidity.

The object of my invention is to produce a car which combines a maximum of strength and rigidity with a minimum of weight. I have accomplished this result by employing a supporting frame structure of novel design and which constitutes a radical departure from the car frame structures now in use.

My improved car frame is an integral structure made up of metal members welded together, and more specifically consists of metal body bolsters, adapted to be carried on a truck or trucks, and a frame work of metal members supported by the bolsters, the members of the frame work being welded to each other and to the body bolster, so that the whole car frame is an integral structure of great strength and rigidity and relatively small weight. Furthermore, the car frame is so designed as to provide suitable spaces for the reception of storage batteries, and is adapted to have secured to it the additional parts necessary to complete the car, such as windows, platforms and hoods, and a roof.

The particular embodiment which I have chosen to illustrate my invention is disclosed in the accompanying drawings in which,

Figure 1 is a perspective view of a portion of my improved welded car frame as seen from within, certain of the members being shown broken or cut off; Fig. 2 is a plan view, partly in section, of the frame structure taken on the line 2—2 of Fig. 3; Fig. 3 is a vertical elevation, partly in section of the same taken on the line 3—3 of

Fig. 2; and Fig. 4 is a perspective view of the entire structure as seen from without.

Similar reference numerals refer to similar parts throughout the drawings.

Referring to the drawings, body bolsters, preferably of cast steel and extending transversely of the frame are shown at 1 and 2. Each of the body bolsters is provided with openings therethrough, through which extend horizontally the longitudinal center sills 3 and 4. The center sills 3 and 4 are preferably of steel I shapes, and are welded to the bolsters at each intersection thereof. Each of the body bolsters is provided with a vertical hole 5 at its middle to receive the truck bolt. Each body bolster is shown provided with a vertical web 6, an upper flange 7, a lower flange 8, and vertical strengthening ribs 9, although other strong and rigid forms of bolster may be employed.

Instead of using cast steel bolsters as described, I may use steel shapes welded together to form the same shape construction as that described, or other suitable form.

To the ends of the center sills 3 and 4, and extending transversely thereof, are welded end sills 10 and 11. The end sills 10 and 11 are of steel channel shapes, and are placed so that each has a vertical web and two horizontal flanges. Each center sill is butted against and welded to the vertical web of an end sill, and the upper flange of each end sill rests upon and is welded to the upper surfaces of the ends of the center sills as is clearly shown in Figs. 1 and 3. The end sills may be rounded at their lower corners as is shown at 12. Extending longitudinally of the car frame are side sills 13 and 14. These sills are of steel channel shapes, and each has a vertical web and two horizontal flanges and is placed so that the channeled surface is disposed toward the interior of the car frame. The side sills 13 are welded to the ends of the end sills and body bolsters. The under structure of the car frame is further strengthened by cross-sills 15 of steel angle shapes extending transversely of the car frame and having their ends welded to the side sills and center sills. Any suitable number of these cross sills may be used. One flange of each cross sill is horizontal, and the upper surfaces of

the cross-sills, side-sills, end-sills, and body bolster are flush with each other and are adapted to receive the car flooring. As an additional means of bracing the understructure, members 16, 17, 18 and 19 of steel angle shapes are provided. Each of these members extends obliquely between an end sill and the adjacent body bolster, and one end is welded to an end sill near the junction of the center sill and the other end is welded to a body bolster near one of its ends. Cross sills 20 and 21 of steel angle shapes and similar to the cross sills 15 extend between the collision members and are welded to the collision members and also to the center sills. At each corner of the car frame gussets 22, 23, 24 and 25 are welded to the upper flanges of the end and side sills at their junctions. All of the parts of the understructure are preferably welded together by the oxy-acetylene process.

The sides of the car frame are formed of vertical posts 26 formed of steel angle shapes butt-welded to the upper flanges of the side sills 13 and 14, and an outer sheathing of steel plates 27 and 28, there being one plate for each side. Each plate extends longitudinally the entire length of the car frame and vertically from the top of the vertical posts 26 to the bottom edge of the side sill 13 or 14, and is welded to the exterior surface of one flange of each of the vertical posts 26, and to the exterior surface of the side sill 13 or 14. Longitudinally extending steel angle shapes 29 and 30 are welded to the outside of the plate 27, and similar members 31 and 32 are welded to the outside of the plate 28. These longitudinally extending members 29, 30, 31 and 32 serve to stiffen and strengthen the side structure. The welding of the plates to the vertical members, side sills, and longitudinally extending stiffening members is preferably accomplished electrically and by the process known as spot welding. Longitudinally extending stiffening and strengthening members 33 and 34 of steel angle shapes are also welded to the vertical members 26 on the interior of the car frame. This welding is also preferably done electrically.

In assembling the structure heretofore described, the parts constituting a side, that is, a plate, vertical members, and longitudinal stiffening members, may be first welded together. The side thus formed is placed in position with reference to a side sill, and welded thereto. The other side and side sill are assembled and united in a similar manner. The remaining parts may then be assembled and welded in place in the following order: an end sill, the body bolsters, the center sills, the other end sill, the collision members, the cross sills, and the gussets.

My improved car frame also includes two lattice girders, each girder resting on and

welded to the cross sills of the understructure and also welded to the side structure. The chief function of these girders is to increase the rigidity of the body. In Fig. 1, only one of these lattice girders is shown 70 the other being omitted to permit the understructure to be shown more clearly. Each lattice girder includes two members 35 and 36 extending longitudinally the length of the car frame and located when in place one 75 vertically above the other. These members 35 and 36 are of steel angle shapes and are united by vertical members 37, the members 37 being welded at their ends to the members 35 and 36. Members 38 extend at right 80 angles to the vertical members 37 and the upper member 35 and are welded to the members 35 and 33. Members 39 extend from the lower member 36 across the horizontal members 38 at an angle of about 45° 85 to the vertical members 37. The oblique members 39 are welded at one end to the lower member 36 at the junction of 36 and 37. Each horizontal member 38 is welded to the corresponding member 39 where the two members cross each other, and one of each pair of these members has metal forced out laterally to contact with the other member as is shown at 40 in Fig. 2. The members 37, 38 and 39 are of steel angle shapes. 90

The members constituting each lattice girder may be welded together electrically and the entire girder then put in place and welded by the oxy-acetylene process to the understructure and sides. When in place 100 the lower member 36 of the lattice girder rests on and is welded to the cross sills 15; the outer ends of the horizontal members 38 rest on and are welded to the member 33 and each end butts against and is welded to a vertical member 26 of the side structure; and each of the upper ends of the oblique members 39 is welded to a vertical member 26. Of each intersecting pair of members 38 and 39, one bears on one side of a flange 110 of a vertical member 26 and the other bears on the other side of the same flange. This necessitates the forcing out of a portion of one of each pair of members 38 and 39 as is shown at 40 in Fig. 2. 115

Each end bulkhead is made up as follows: A steel angle iron having two vertical portions 41 and 42 and an arched portion 43 is supported and welded to the corners of the under structure, the exterior surfaces of the flanges being flush with the exterior corners of the understructure at the junctions of the side and end sills. Within the member 41, 43, 42, and forming with the vertical portions 41 and 42 channel shaped posts, are steel angle shapes 44 and 45 welded to the end sills at their lower ends, and also welded to angles 41 and 42 at their junction therewith. 120

The upper ends of the members 44 and 45 130

are shaped to fit the curves of the member 41, 43, 42 and are welded thereto. Each bulkhead has also two vertical members 46 and 47 shown as hollow square posts. These members are also of steel and have their lower ends both welded to an end sill and their upper ends welded to the curved angle 43. The space between these vertical members may be utilized for the car door

10 way.

Horizontal strengthening members 48 and 49 extend between the posts 44 and 46 and have their ends welded to the said posts. These members are of steel channel shapes. 15 Similarly, members 50 and 51 extend between and are welded to the posts 47 and 45. A channel member 52 curved in the form of a seat arm also extends between and is welded to the posts 44 and 46, and a similar member 53 extends between and is welded to the posts 47 and 45.

The parts of the bulkhead hereinbefore described are preferably oxy-acetylene welded. The plates 27 and 28 are welded, preferably by electrical spot welding, to the posts 41 and 42 at one end of the car frame and to the corresponding posts at the other end. The members 33 and 34 are welded to the posts 44 and 45 respectively and the member 30 35 to the member 49. The member 36 rests upon and is welded to the end sill 11. The structure at each of the four corners of the car frame is the same.

A steel plate 54 shaped as shown in Figs. 35 1 and 4 and provided with an opening 55 for a window or for ventilation, is spot welded to the upper part of each bulkhead on the outside. On the outside of the steel plate 54 is welded a curved steel angle shape 54^a 40 conforming to the shape of and adapted for the attachment of a platform hood.

The center posts 56 and 57 and the arch 58 are formed in a single piece of steel, channel shaped, and this piece conforms in outline to the bulkheads. This intermediate member takes the place of two of the vertical members 26 at the center of the car, and rests upon and is welded at its ends to the side sills 13 and 14. The side plates 27 50 and 28 are spot welded to the exteriors of the post portions 56 and 57. These post portions 56 and 57 are also welded to the members 33 and 34, and each post portion is welded to a pair of intersecting members 38 55 and 39. If desired, additional intermediate members like the member 56, 58, 57 may be used in a single car frame. Steel bands 59 and 60 extend along the upper portion of the car frame, and are spot welded to the 60 exteriors of the posts 41, 56 and 41, and 42, 57 and 42 respectively. The steel bands 59 and 60 together with the bulkhead plates 54 form a continuous metal band surrounding and connecting the upper portions of the car frame.

At the end of the car frame the space between the posts 41, 44 and 46 and below the cross piece 52 is covered by a steel plate 62 spot welded to the members mentioned and also to the end sill 11 and the cross piece 49. 70 A similar plate is provided at each of the corresponding portions of the car frame. These plates are perforated for a purpose hereinafter described.

The lattice girder is adapted to receive the 75 car seats, and the space beneath the car seats may be utilized for the reception of storage batteries to furnish power and light for the car. The perforations in the plates 62 serve to ventilate the battery containing space.

It is to be noted that the entire structure 80 when completed is a unitary steel structure and combines a maximum of strength and rigidity with a minimum of weight.

The steel bands 59 and 60 have welded to 85 them on the inside small steel angles 61 vertically over the members 26. The steel angles together with the vertical members 26 are adapted to support the wooden window posts of the car.

All of the members of my improved car 90 frame are preferably rolled shapes of open hearth steel, except the body bolsters which are preferably steel castings. Obviously, the welding may be done by any suitable method.

Having now described my invention, what I claim as new and desire to secure by Letters Patent, is as follows:—

1. A car frame comprising a unitary integral structure, comprising metal body bolsters, a superstructure and an understructure, both composed of steel shapes and said superstructure including side posts and lattice girders running the length of the car, all of the said parts being welded together to 100 form an integral structure, substantially as described.

2. A car frame comprising a unitary integral structure, comprising metal body bolsters, a superstructure and an understructure, both composed of steel shapes and said superstructure including lattice girders running the length of the car, a steel side structure and end bulkheads, all of said parts being so joined together as to form an integral structure, substantially as described.

3. A car frame comprising a unitary integral structure, comprising an integral metal understructure, an integral metal superstructure and metallic lattice girders running the length of the car, above the floor line, all of said parts being so joined together as to form an integral structure, substantially as described.

4. In a car frame structure, the combination of an understructure, side and end structures welded thereto, lattice girders welded to the understructure, side and end structures each of said structures being composed of metal members welded together, and a 125 130

continuous steel band welded to and connecting the end structures, substantially as described.

5. In a car frame structure, the combination of an understructure, side, end and intermediate structures welded thereto, lattice girders welded to the understructure, side, end and intermediate structures, each of said structures being composed of metal members

welded together, and a continuous steel band 16
welded to and connecting the end and intermediate structures, substantially as described.

This specification signed and witnessed
this 18 day of Feby. 1911.

RALPH H. BEACH.
